UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 23,618, dated September 4, 1894.

Application filed August 3, 1894. Serial No. 519,370. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental scrolls arranged to form a series of panels 10 with a heraldic form of ornament of shield-like form in the center of said panels and also formed of ornamental scrolls as represented in the accompanying drawing.

The border or upper portion of the design is 15 formed of a series of ornamental scrolls with

heraldic form of ornaments also formed of ornamental scrolls and ornamental shield ornaments arranged as shown in the drawing.

What I claim is—

1. The design for wall paper herein shown 20 and described.

2. In the design for wall paper, the border herein shown and described.

Witness my hand this 31st day of July, 1894.

CHARLES BOOZE.
